UNITED STATES PATENT OFFICE.

OTTO H. L. WERNICKE, OF GRAND RAPIDS, MICHIGAN.

CABINET-FRAME CLAMP.

SPECIFICATION forming part of Letters Patent No. 625,482, dated May 23, 1899.

Application filed March 17, 1898. Serial No. 674,168. (No model.)

To all whom it may concern:

Be it known that I, OTTO H. L. WERNICKE, of Grand Rapids, county of Kent, and State of Michigan, have invented certain new and 5 useful Improvements in Cabinet-Framing Clamps, of which the following is a specification.

My invention relates to machines wherein the several parts of crates or boxes may be placed while being secured together; and the objects of the invention are to provide means for clamping, preferably, the ends of a crate or box to hold the same securely while the other parts are being nailed, screwed, or otherwise secured thereto, to the end that the parts composing the back, bottom, and top will occupy in each crate the same relative position with respect to the ends and will when secured together form crates of uniform size 15 irrespective of variations in the dimensions of the parts or the warping of the material composing the same, and, further, to provide adjustable clamping devices to permit the parts of crates or boxes of different sizes to be 20 placed in the machine and secured together.

The invention consists in a suitable frame, clamping-jaws supported by said frame and adapted to lock therein, and means for opening and closing said jaws.

Further, the invention consists in providing clamping-jaws having both a rocking movement in a supporting-frame and a longitudinal movement in their bearings.

Further, the invention consists in providing means in connection with said jaws whereby the proper position of the several parts composing the back, bottom, and top of the crate or box with respect to the ends may be determined.

Further, the invention consists in providing means in connection with said jaws whereby the proper position of interior partitions may be determined.

Further, the invention consists in various 45 constructions and combinations, all as hereinafter described, and particularly pointed out in the claims.

In the accompanying drawings, forming part of this specification, Figure 1 is a perspective view of a cabinet-frame clamp embodying my invention. Fig. 2 is a transverse sectional view of the machine, the various

positions which a crate or box assumes during the process of nailing being indicated by dotted lines. Fig. 3 is a perspective of a completed crate. Fig. 4 is a plan view of the clamping-jaws when open. Fig. 5 is a similar view with the jaws closed. Figs. 6, 7, 8, 9, and 10 are detail sectional views showing the various steps and the positions of a crate 55 during the process of fastening the parts together. Fig. 11 is a section of a completed crate. Fig. 12 is a detail of a modified form of clamp for use in determining the position of interior partitions.

In the drawings, 2 represents the frame of the machine, which may be of wood or iron, if preferred, and preferably of the rectangular form shown. On the top of the frame 2, at each end thereof, are standards 3, having 60 bearings 3' at their upper ends to receive the ends of the exteriorly-threaded rock-shaft 4, upon which two or more clamps are mounted, each comprising normally stationary jaws 5 65 and 6, alternating in position on the shaft with 70 sliding jaws 7 and 8. The stationary jaws are held in position on the shaft by lock-nuts 7 and 8, and one of the stationary jaws bears at one end against the bearing 3', as shown in Figs. 4 and 5. The lock-nuts 7 7 75 and 8 may be moved back and forth along the shaft 4, thereby permitting the adjustment 80 of the stationary jaws in any desired position to enable the operator to clamp the parts of the different-sized crates during the process 85 of securing them together. These lock-nuts not only serve to hold the jaws in position upon the rock-shaft, but also regulate the movement of the sliding jaws toward the stationary jaws, and as the nuts correspond substantially in thickness to the thickness that it is desired to make the end parts of a crate 90 the operator is able to determine whether the parts placed between the jaws are of proper thickness without the necessity of making 95 any measurements, for should an end part be placed between the jaws and prove to be considerably thicker than the collars or lock-nuts the operator would find it difficult or impossible to move the locking or cam lever past 100 the center, and, on the other hand, if the material was thinner than the collars the end part would be loose in the jaws, and in either case the operator would at once discover that

the material was defective before it was worked into a crate. The jaws 6 6 are slidably arranged upon the rock-shaft 4 and are prevented from swinging thereon by a sliding key or spline 6', or in any other suitable way. To aid in moving the sliding jaws upon the rock-shaft, I provide curved links 14 and 14', having their inner ends connected, respectively, to lugs or ears 13" and 13' upon the inner stationary and sliding jaws of the clamps. The outer ends of said links are connected, respectively, to locking cam-links 15 and 15', which are in turn pivotally connected to lugs or ears 15"" and 15" upon the outer sliding and stationary jaws of the clamp. When these locking-levers are operated, the sliding jaws will be moved back and forth upon the rock-shaft in the same direction to open or close the jaws, and when the jaws are nearly closed the pivotal point between the operating parts will pass over the center, thereby locking the jaws together without the necessity of using a ratchet or similar mechanism. The alternate arrangement of the jaws permits a crate to be readily removed from the machine, which could not be done if the machine were constructed with both inside or outside jaws stationary, owing to the pressure of the the stationary jaws against the ends of the crate.

Both the stationary and sliding jaws are provided, preferably, with grooved or corrugated faces, as shown in Fig. 1, one of the jaws in each clamp being provided with a bracket 11, having a shoulder or stud 12 projecting laterally therefrom and resting upon a block 13, arranged upon the top of the frame beneath the clamps and adapted to hold the clamps in a substantially horizontal position while the parts are being placed therein preparatory to fastening them together. Adjustably secured to the inside jaws, as shown in Fig. 1, are blocks 16, having shoulders 17 to receive the edges of the slat that is to be nailed to the ends of the crate to enable the operator to determine the exact position which the slat should occupy with reference to the ends to which it is to be nailed.

At one end of the shaft 4 is a lever 18, carrying an adjustable weight 19, said lever being adapted to engage a catch 20, which is actuated by a strap-spring 21, secured to the frame 2. A pivoted arm 22 is provided on the frame of the machine in position to be controlled by the operator by foot or knee pressure and is connected with the catch 20 by a rod 23. Suspended in the frame 2 by bolts or screws 24 is a frame or platform 25, parallel with the shaft 4 and provided on its upper surface with the transverse blocks 26, opposite the blocks 13 at the front of the machine. Suitable means are provided at the upper end of the screws or bolts 24, such as a head with a transverse opening to receive a rod or bar for operating the screw, to raise or lower the platform 25; but other means may be employed, if desired.

At the rear of the machine upon standards 27 and 28 are telescoping ways 29, arranged transversely upon the machine and carrying a nail-receptacle 30, having legs or standards 31, secured to the sliding sections of the ways 29. A link 32 pivotally connects the nail-receptacle with a stud 33 upon a lever 34, that is clamped to the shaft 4 between the clamping-jaws or at either end of said shaft outside of said jaws.

For use in determining the proper position of longitudinal shelving in a crate I may provide the inside jaws with parallel slots 36, Fig. 12, to receive the shelving and hold the same in proper position while being secured in a crate. Suitable templets may be provided upon the rock-shaft between the jaws to be used in determining the proper spacing 85 between pigeonholes when it is desired to fit up a box or crate in that way.

When it is desired to secure the parts of the crates together, the ends are placed within the clamps, and by means of the cam-levers 90 15 and 15' the sliding jaws are moved along the shaft until the ends of the crate are firmly clamped in position and any warp or twist that may exist in the material removed. The operator then places a slat upon the upper 95 edge of the end parts and, aided by the guides 16, determines exactly the proper position of the slat, so that the slat of each crate will occupy the same relative position with reference to the ends when the crates are completed. The slat is then nailed to the ends, and the clamping-jaws are then raised to the position shown in Fig. 7, when the lever 18 will engage the catch 20 and hold the crate and jaws in an elevated position while the back of the 105 crate is being fastened in place. This being done, the operator, by means of the lever 22, disengages the catch 20 from the lever 18 and permits the shaft 4 to rock, carrying with it the clamping-jaws to the position shown in 110 Fig. 8 of the drawings, when the upper edges of said jaws rest upon the blocks 26, as shown in said figure. Slats forming the bottom of said crate may then be nailed in position upon the ends and the crate completed. During 115 the process of nailing the parts together the nail-receptacle 30 being connected with the rocking shaft 4 will be moved back and forth with the sliding sections of the ways 29, adjusting itself automatically to the different 120 positions of the crates, so that it will always be within easy reach of the operator.

By means of the vertically-adjustable platform at the rear of the machine the ends of crates of different sizes may be placed in the 125 clamping-jaws and the top and bottom slats nailed thereto while the ends, during the process of nailing, are maintained in a substantially horizontal position, as indicated in the figures showing the different positions of the crate while the parts are being fastened together. The advantages of this device lie in the fact that the slats forming the tops and bottoms of a series of interlocking crates may

be secured to the ends in their proper position without any measurements being taken by the operator preparatory to nailing the parts together. This of course greatly facilitates 5 the work of nailing up the crates, and as the slat at the top of each crate fits into the space between the two slats on the bottom of the superimposed crate it is very important that these slats should occupy the same relative 10 position in each crate with reference to the ends; otherwise when the crates are placed one above another to form a bookcase the slats either would not interlock easily or would fit so loosely as to render the bookcase 15 extremely unstable and unsafe. Further, as each crate or box is provided at either end with a device for joining it to the abutting crate, it is of the utmost importance that the outside surfaces of the end pieces should be 20 exactly uniform, in order that a perfect joint may be made between the ends of the abutting crates and the forward edges of the crates be in perfect alinement when the several crates are joined together to form a book- 25 case. The clamps being adjustable upon the rock-shaft 4 permits the operator to place the end of crates of different lengths in the machine and lock them securely while the slats and back pieces are nailed thereto, and by 30 the use of the lock-nuts or collars of uniform thickness uniform outside dimensions of the crates are insured, for these collars, as heretofore described, control the pressure upon the end parts of the crate, regulate the travel 35 of the sliding jaws, and enable the operator without measuring to determine whether the material to be used is of suitable thickness.

I do not confine myself to the use of two clamps upon the rock-shaft, as shown and 40 described in this application, as it is obvious that a greater number may be used and that additional devices may be placed upon the shaft between the clamps to adapt the machine for use in arranging shelving or pigeon-hole-partitions within a crate, nor do I confine myself to the details of construction 45 herein shown and described, as it is obvious that the same may be varied without departing from my invention.

50 Having thus described my invention, I claim as new and desire to secure by Letters Patent—

1. A cabinet-frame clamp, comprising a supporting-frame, a rock-shaft mounted therein, 55 independently-operable clamps carried by said shaft, each comprising a normally fixed and sliding jaw alternately arranged, means connecting, respectively, the fixed and sliding jaw of each clamp for moving the sliding 60 jaw toward or from the fixed jaw and said clamps being adjustable upon said shaft to receive the parts of frames of different size.

2. A cabinet-frame clamp, comprising a frame, a rock-shaft mounted thereon, nor- 65 mally fixed and sliding jaws alternately ar- ranged upon said shaft, said jaws being par- tially revoluble with said shaft and adjust-

able thereon, means for moving said sliding jaws toward or from said fixed jaws, and means for limiting the travel of the former 70 toward the latter and for locking the normally-fixed jaws when adjusted upon said shaft.

3. A cabinet-frame clamp, comprising a frame, a threaded rock-shaft mounted therein, 75 clamps comprising normally fixed and sliding jaws alternately arranged upon said shaft, means for operating the sliding jaws to move the same toward or from the fixed jaws of the respective clamps, lock-nuts 7 provided on 80 said shaft between the fixed and sliding jaws of the respective clamps, to aid in retaining the fixed jaws in position and to limit the travel of the sliding jaws toward said fixed jaws, substantially as described. 85

4. A cabinet-frame clamp comprising a supporting-frame, clamps mounted therein, each comprising a normally fixed and sliding jaw alternately arranged, said clamps being adjustible to or from each other, partially revo- 90 luble and independently operable.

5. The combination, with a supporting-frame, of a rock - shaft mounted therein, clamps adjustably arranged upon said shaft and adapted to describe a partial revolution 95 therewith, each clamp comprising alternately fixed and sliding jaws, links 14 and 14' piv- otally connected to alternate jaws, and cam- levers 15 and 15' pivotally connected to the remaining jaws and to said links, substan- 100 tially as described.

6. The combination, with a supporting-frame, of a threaded rock-shaft mounted in bearings thereon, clamps independently and adjustably arranged upon said shaft, each 105 clamp comprising a normally fixed and a slid- ing jaw alternately arranged, independent means for moving said sliding jaws toward or from the fixed jaws of the respective clamps, and lock-nuts arranged upon said shaft to 110 limit the travel of the sliding jaws toward the fixed jaws and control the adjustment of the clamps upon said shaft.

7. A cabinet-frame clamp comprising a sup- 115 porting-frame, clamps mounted therein, each comprising a normally fixed and sliding jaw alternately arranged, means for moving said sliding jaws toward or from said fixed jaws, and said clamps being adapted to describe a partial revolution to permit access to the 120 sides and bottom of the cabinet or crate without removing the same from the clamps, sub- stantially as described.

8. The combination, with a supporting-frame, of a rock - shaft mounted thereon, 125 clamps comprising normally fixed and slid- able jaws arranged upon said shaft and adapt- ed to make a partial revolution therewith, means for operating the sliding jaws to and from the fixed jaws of the respective clamps, 130 and means for locking the clamps in an up- right position during their partial revolution, substantially as described.

9. The combination, with a supporting-

frame, of a rock - shaft mounted therein, clamps arranged at intervals upon said shaft and adapted to rock therewith, means for opening and closing said clamps, a platform 5 provided at the rear of said frame, and means for raising and lowering said platform, substantially as described.

10. The combination, with a supporting-frame, of a rock - shaft mounted therein, 10 clamps arranged at intervals upon said shaft and adapted to rock therewith, said clamps comprising normally fixed and sliding members, means for operating said sliding members, to close and open said clamps, and an 15 adjustable guide or block carried by said jaws and projecting above the upper edge thereof, for the purpose set forth.

11. The combination, with a supporting-frame, of a rock - shaft mounted therein, 20 clamps arranged at intervals upon said shaft, means for opening and closing said clamps, a nail-receptacle supported in guides upon said frame, a lever 34 upon said shaft and a link pivotally connecting said lever and said nail-receptacle, for the purpose set forth. 25

12. The combination, with a supporting-frame, of a rock-shaft mounted in bearings thereon, clamps arranged at intervals upon said shaft, each comprising a normally fixed 30 and sliding member alternately arranged, the lock-nuts upon opposite sides of said fixed member, the links 14 and 14' alternately connected with said fixed and sliding members, the cam-levers 15 and 15' alternately connected with said fixed and sliding members and with said cam-links 14 and 14', face-plates carried by said jaws, the blocks 13, the vertically-adjustable platform at the rear of said frame and the blocks 26 carried by said platform opposite said blocks 13, for the purpose 40 set forth.

13. A cabinet-frame clamp comprising a supporting-frame, clamps mounted therein each comprising a normally fixed and sliding jaw 45 alternately arranged, means for moving said

sliding jaw toward or from said fixed jaw, and said clamps being adapted to describe a partial revolution to permit access to the sides and bottom of the cabinet or crate without removing the same from the clamps, and said 50 clamps being also adjustably supported within said frame toward or from each other to permit the construction of cabinets of different size, substantially as described.

14. The combination, with a supporting-frame, of clamps mounted in rocking bearings therein, each clamp comprising a fixed and sliding member alternately arranged, means for opening and closing said clamps, and the 55 inside jaws of said clamps being provided with parallel slots, for the purpose set forth.

15. The combination, with the supporting-frame, of a rock - shaft mounted therein, clamps arranged upon said shaft and having a partial revolution therewith, means for opening and closing said clamps, said clamps normally resting upon said frame at the limit of their travel in one direction, and a vertically-adjustable mechanism for supporting said 65 clamps at the limit of their travel in the opposite direction, substantially as described. 70

16. The combination, with the supporting-frame, of a rock - shaft mounted therein, clamps arranged at intervals upon said shaft and comprising alternately fixed and sliding 75 jaws, means for operating said sliding jaws to open and close said clamps, said clamps being adapted to perform a partial revolution with said shaft, a lever 18, a catch 20 to engage said lever during the rocking of said 80 shaft, a spring 21, a rod 23 and an arm 22 connected to said rod, substantially as described.

In testimony whereof I have hereunto set my hand this 15th day of February, A. D. 85 1898.

OTTO H. L. WERNICKE.

In presence of—

NAN A. RYAN,
HUGH E. WILSON.
